DISPLACEMENT DIPPER PUMP

Neo S. Serinis, Gloucester, N. J., assignor to New Process Rayon, Inc., Gloucester, N. J., a corporation of Delaware

Application June 8, 1938, Serial No. 212,523

6 Claims. (Cl. 221—97)

The present invention relates to a pump for feeding liquids such as chemicals or solutions thereof or the like at a small but practically uniform rate to a location at which such solution or liquid is to be utilized, and to an apparatus including such device.

More specifically it relates to a means for feeding liquids, particularly corrosive liquids or such as might harden, crystallize, or otherwise produce obstructions in small conduits or orifices.

The device embodies one or more pumps each having a displacement member, a reservoir for the liquid to be fed and a reciprocating dipper for feeding the liquid to be pumped, together with a suitable outlet for the liquid.

The invention also embodies two pumps geared together so as to operate alternately. This arrangement is advantageous in that it will give a more continuous flow from the pumps than would a single pump, since the two pumps will produce a flow wherein the fluctuations are considerably less than in a single pump.

The two pumps may also be used to feed two different liquids while maintaining strict proportionality between the outputs of the respective pumps or maintaining strict equality where such equality is necessary. This ratio may be adjusted very readily by means of the two displacement members and in this way the combination of two pumps may play a very important part wherever it is necessary to supply such two different solutions or chemicals at a constant ratio to one another.

The apparatus is of general application in the art of feeding liquids, particularly where small flows of corrosive liquids are involved.

In the specific instance illustrated in the present case it is shown as applied to an acid drip device for rayon or other artificial fiber.

For a clear understanding of the invention reference is to be had to the accompanying drawing wherein:

Figure 1 illustrates a pair of pumps and associated parts, this view being a diagrammatic axial section through such multiple pump structure, and

Figure 2 is a perspective view of a portion of the structure shown in Figure 1, parts being omitted and other parts being shown in section for clearness of illustration.

In the drawing, for each pump, 1 represents a container made of any suitable material, for example metal, for holding the acid or other

chemical or liquid which is to be applied to the rayon.

In order to pump or feed the acid or liquid 2 from said container 1, use is made of a dipper 3 here shown as a vessel having advantageously a convex lower end and which is made small enough to be submerged bodily within the liquid in the container 1. The dipper has a discharge lip as shown at 4 from which liquid may drip or flow, by gravity.

10 The dipper is supported in a holder here shown as a tubular member 5 which is connected with an operating member 7. Means are provided for reciprocating the dippers, these means comprising a shaft 49 which is given oscillating motion 15 from any desired source, not illustrated, and which carries a pinion 48 meshed with two vertically arranged rack bars 46 and 47 respectively. The rack bar 46 is secured to a strap 44 which is capable of reciprocating movement in the slot 20 50 of end plate 38 while the rack bar 47 is correspondingly secured to the strap 45 which similarly reciprocates vertically in the slot 51 also formed in said end plate.

Upon referring to Figure 2, it will be seen that 25 the collar 6 which encircles the dipper 3 has wings 52 thereon which may be clamped together by means of a screw 53 so as to hold the dipper firmly to the part 7.

The elements 43 which support the collars 6 30 holding the displacement members 8 may be secured to the longitudinal members 39 and 40 of the frame in any suitable manner as by the spot welds 41 indicated in Figure 1.

For smoothness of operation the shaft 49 may 35 be extended to the opposite end of the frame and duplicate racks 46 and 47 secured to the opposite ends of the straps 44 and 45 respectively may be provided to cooperate with a duplicate pinion 48 secured to the other end of the shaft 40 49 so that both pinions will operate in unison and will reciprocate the straps 44 and 45 in unison at their opposite ends so as to prevent any possibility of binding.

The end plates 38 together with the longitudinal members 39 and 40 which are secured thereto form a supporting frame for the two pumps and this frame in turn stands on a pair of supports 37, one at each end, only one, however, being shown here.

50 The reciprocating members 7 are secured to the elements 44 and 45 in any desired way, for example by spot welding as indicated at 42.

Cooperating with the dipper 3 there is a plunger or displacement member 8 which may be sup-

ported by any suitable clamp or the like here shown as a cylindrical clamp 9 which releasably grasps the member 8 to permit vertical adjustment of the displacement member 8 if desired. 5 Each cylindrical clamp 9 may be split as shown and terminate in the wings 35 which may be drawn together by means of the clamping screw and nut 36 as best shown in Figure 1, to permit such releasable clamping of the member 8. Attached to each container 1 there are supports 11, 11 with clamping screws 12, 12 which will engage the stem 13 of a vessel 31 and hold said vessel in proper position so that its funnel-top 14 will come below the downwardly bent end 23 10 of a pouring spout 10 which is also secured to the vessel 1. This spout may conveniently rest upon and be secured to one of the flanges 24. 15 25 formed at the top of the container 1. The vessel 31 also has at its lower end a body or bulb 15 with an outlet opening 16 into which fits loosely the upper bent end of a rod 18 which serves to conduct liquid from said bulb downward by capillary action as disclosed in greater detail in copending case Serial No. 212,524, filed of even 20 date herewith.

In operation, upon reciprocation of the operating member 7 the dipper 3 will be depressed below the surface of the acid or other liquid 2 in the container 1 so that the dipper will become filled 30 with such liquid, this operation occurring upon each downward stroke of the respective dipper.

Thereupon, when member 7 raises the dipper, the latter will first discharge the excess of its contents above the level of its discharge lip 4, 35 which will have taken place before the dipper has risen far enough to bring the liquid therein into contact with the lower end 28 of the plunger 8. This lower end may conveniently be made convex as illustrated so as to make it easy to keep 40 clean, although its exact shape is not an important feature of the present invention.

Upon further ascent of the dipper the plunger 8 will begin to become immersed in the liquid contents of said dipper, in other words, it will begin 45 to displace some of said contents which will thereupon discharge through the pouring spout 4. Immediately below this pouring spout and advantageously in vertical alignment with its discharge edge, there is a drip member 26 forming part of 50 the pouring spout 10 which will graze the lip 4 when the dipper ascends and strike off any excess liquid therefrom. The plane of the drip member or baffle 26 also serves as a defining plane in that any liquid flowing to the right of said wall will 55 flow down the incline of the discharge spout 10 and through its downwardly bent discharge end 23 into the funnel 14. It is clear that the dipper 3 will continue to discharge some of its liquid contents 6 as long as it continues to rise, that is, 60 as long as the plunger 8 continues to become immersed more deeply in the said liquid.

Because of the fact that the liquid flows with a certain horizontal velocity from the outlet spout 4, that is, it does not merely drip down therefrom, the flow of such liquid will overshoot the plane of the baffle 26 and, therefore, it will flow down the inclined discharge spout 10 instead of dripping back into the container 1.

Upon the next movement of the member 7 the 70 dipper will again become submerged in the container 1 and will take up a new charge of liquid, whereupon the action above described will be repeated, and so on.

The liquid which flows into the funnel 14 will 75 find its way down through the neck 13 of the ves-

sel 31, into the bulb or body portion 15 thereof and thence out through the orifice 16 and along the rod 18, as described in greater detail in the said copending case.

It is obvious that upon each vertical reciprocation of the dipper 3 the same amount of liquid will be discharged from its spout 4 into the pouring spout 10, this amount being equal to the volume of the submerged portion of the plunger 8. This affords a simple and convenient means for adjusting the rate of feed of liquid, for it is necessary merely to raise or lower the plunger 8 within its clamp 9 so as to vary such submerged volume.

A difficulty encountered in pumps or feed devices of the conventional types is that where the feeds are relatively small or where the liquids being fed are corrosive chemicals or solutions thereof or such as may solidify or produce deposits of any kind, the small passages necessary in such pumps readily become clogged so as to obstruct the flow and eventually stop it altogether or become eaten away so as to increase their size and produce a gradually increasing flow, or else certain vital parts of the pump mechanism such as valves or the like may become corroded, and stuck 20 or leaky as a result, and various other disadvantages only too well known to those skilled in the art may occur therein.

The present device obviates all these disadvantages in the first place by providing a pump 30 which has no valves whatever, and which has no parts which fit closely on any others to produce a pumping effect such as a pressure or a suction, with the further incidental advantage that it is not necessary to do any accurate machining or 35 fitting of parts whereby consequently friction also is eliminated entirely so that no wear takes place and no "sticking" can result. The parts of the present pump are all very simple and are readily accessible for cleaning and repair or replacement.

A further advantage of the device is that all the parts are relatively simple in shape and structure and may be readily made with sufficient uniformity by ordinary manufacturing processes.

While the device has been herein described as intended mainly for the feeding of chemicals, and particularly of corrosive chemicals such as acid or alkaline solutions, or such as might produce obstructions, it is, of course, also of general application and may serve also for the feeding of 50 water or other harmless, neutral or non-clogging liquids with equal efficiency.

It is possible that the pump comprising the displacement member and the dipper might be 55 used to discharge its contents to some other mechanism than the vessel 31 and where such conditions exist, it will be evident that the pump may be used independently.

It will be noted that two pumps have been disclosed in the present case and that they are duplicates of one another as to all their essential working parts. However, it will be seen that the dipper or bucket of one of the pumps will be at the top of its stroke when the dipper of the other is 65 at the bottom of its own stroke, that is, the two pumps are here geared so as to operate alternately. This arrangement may be advantageous in certain cases as it will give a more continuous flow from the pumps than would a single pump, since 70 the two pumps will produce a flow wherein the fluctuations are considerably less than in a single pump.

It is, of course, also possible that the two pumps 75 may feed two different liquids while maintaining

strict proportionality or maintaining strict equality where such is necessary. This may be adjusted very readily by means of the two displacement members and in this way the combination of the two pumps may play a very important part wherever it is necessary to supply such two different solutions or chemicals at proportional rates.

While a specific embodiment of the device has been disclosed herein, it is obvious that this embodiment merely represents one particular form of the invention, which is not limited thereby but is understood to be defined only by the following claims.

15 I claim:

1. A feeding device for liquid, comprising a reservoir for the liquid, a dipper, means for reciprocating the dipper to alternately submerge it and elevate it, a displacement member, and means for supporting it in cooperative relation to the dipper, to cause it to displace liquid therefrom.

2. A feeding device for liquid, comprising a reservoir for the liquid, a dipper, means for reciprocating the dipper to alternately submerge it and elevate it, a vertically adjustable displacement member, and means for supporting it in cooperative relation to the dipper, to cause it to displace liquid therefrom.

3. In a device as in claim 1, a pouring spout on the dipper to conduct its discharge to a location beyond the confines of the reservoir.

4. A proportional feeding device for two liquids comprising a pair of feeding devices each comprising a reservoir for the liquid, and a dipper, means for reciprocating the dippers in opposite phase to one another to alternately submerge and elevate them, a pair of vertically adjustable displacement members and means for supporting them in cooperative relation to the corresponding dippers to cause them to displace liquid therefrom.

5. A proportional feeding device as defined in claim 4, wherein the means for reciprocating the dippers comprises a rack attached to each dipper and a single pinion in mesh with both racks.

6. A feeding device for liquid comprising a reservoir for the liquid, a dipper, means for reciprocating one with respect to the other vertically to alternately submerge the dipper and remove it from the liquid, a displacement member, and means for supporting it in cooperative relation to the dipper to cause it to displace liquid therefrom upon relative movement between the dipper and displacement member.

NEO S. SERINIS.
